UNITED STATES PATENT OFFICE.

LE DRU R. POMEROY, OF TOLEDO, OHIO, ASSIGNOR TO THE TOLEDO BUTTON MACHINE COMPANY, OF TOLEDO, OHIO, A CORPORATION OF OHIO.

SHOE-BUTTON-FASTENING MACHINE.

1,240,874.

Specification of Letters Patent. Patented Sept. 25, 1917.

Application filed October 9, 1916. Serial No. 124,542.

To all whom it may concern:

Be it known that I, LE DRU R. POMEROY, a citizen of the United States, and a resident of Toledo, in the county of Lucas and State of Ohio, have invented a certain new and useful Shoe-Button-Fastening Machine; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

15 This invention relates to shoe button fastening machines, and particularly to the button feed mechanism thereof.

The object of my invention is the provision, in a machine of the class described, 20 of means which is automatically operable, during an operation of the machine, to eject from the button feed guide of the hopper buttons which are not disposed in proper feeding position thereon, thereby preventing 25 possibility of clogging in said guide and enhancing the practicability and commercial value of such machines.

The invention is fully described in the following specification, and while, in its 30 broader aspect, it is capable of embodiment in numerous forms, a preferred embodiment thereof is illustrated in the accompanying drawings, in which—

Figure 1 is a side elevation of a machine 25 embodying the invention with parts removed. Fig. 2 is an enlarged side elevation of the hopper portion of the machine with parts in section and with the button elevating slide raised to kicker-slide tripping position. Fig. 3 is an enlarged perspective view of portions of the invention illustrating the relative position of the kicker slide operating parts immediately prior to the tripping of said slide, and Fig. 4 is a top 40 plan view of the hopper and associated parts.

Referring to the drawings, 1 designates the button holding hopper of a button setting machine, 2 the inclined guideway leading from the front side of said hopper at its upper portion, which guideway is longitudinally grooved on its top to permit the button eyes to extend down therein, as well understood in the art, and 3 designates the 45 vertically movable button elevating slide,

which is commonly employed to periodically raise buttons within the hopper into position to pass onto and down the guideway 2. The lower end of the slide 3 extends down through the bottom of the hopper and has 50 pin-and-slot connection with an operating lever 4, which lever is pivoted to the machine-frame, as at 5, and is connected in a well known manner to the operating foot pedal 6, whereby the lever is rocked to elevate the slide at each depression of the pedal.

The feature comprising the present invention consists in mounting a vertically movable kicker slide 7 in a portion of the guideway 2 within the hopper and to extend said kicker slide down through the bottom of a hopper in position to be engaged and raised a predetermined extent by a tripping pawl 8 at each slide raising movement of the lever 4. For this purpose the lower end of the kicker slide 7 is provided without the hopper with a forwardly extending arm 9 having a lip 10 projecting outward therefrom in position to be engaged by a lip 11 on the 75 pawl 8 when the pawl is moved upward. The pawl 8 is pivoted to the lever at the rear of its fulcrum, as at 12, and is permitted to have limited rocking movements relative to the lever by a pin 13 projecting from the 80 lever into a transverse slot 14 in the tail-piece of the pawl, the weight of the tail-piece causing the lip 11 to normally stand in position to engage the lip 10, as shown in Fig. 3. The kicker slide 7 is normally held 85 in lowered position by a spring 15, which connects the lip 10 to a subjacent portion of the frame.

When the pawl 8 has raised the kicker slide a predetermined extent, upon an upward movement of the lever 4, the lips 10 and 11 slide from engagement and the kicker slide is returned to its lowered position by the spring 15, while the lever continues its upward movement to elevate the slide 3 to 95 its full extent. The pivotal mounting of the pawl permits its lip to pass the lip 10 on the downward stroke of the lever and pawl, as is apparent.

The upper end of the kicker slide 7, in 105 the present instance, is angled forward to adapt it to project partially under the stripper plate 16 over the guideway 2, and also to adapt it when lowered to have its descent stopped by shouldering against a register 110

ing portion 17 of the guideway groove bottom out of obstructing relation to the button eyes moving down the guideway.

It will be understood that should a button 5 not be properly deposited on the guideway 2 for feeding down the same, it will be stopped by contact with the stripper-plate 16 and will then be kicked from the guideway by the kicker slide, when raised, and 10 permitted to fall back into the hopper. The disengaging of the kicker slide and pawl lips 10 and 11 is timed to take place slightly before the elevating slide 3 has reached the top of the guideway 2 so that the kicker 15 slide will have removed any improperly positioned button from the guideway and returned to its normal inoperative position by the time the slide 3 has been raised into position for the buttons to slide therefrom 20 onto the guideway 2.

I wish it understood that my invention is not limited to any specific construction, arrangement or form of the parts, as it is capable of numerous modifications both in the 25 parts and the arrangement thereof without departing from the spirit of the claims.

Having thus described my invention, what I claim as new, and desire to secure by Letters Patent, is—

- 30 1. In a machine of the class described, the combination with a hopper having a button delivery guideway, and means operable to elevate buttons within the hopper to said guideway, said means having a button elevating slide and an operating lever attached thereto, of a member movable to kick improperly positioned buttons from said guideway, means normally retaining said member in inoperative position, and means 35 operable by the lever of said first means at each button elevating movement thereof to move said member to button kicking position and then to release the member to permit it to return to inoperative position.
- 40 2. In a machine of the class described, the combination with a hopper having a button delivery guideway, a button elevating slide in said guideway, and a lever connected to said slide and operable to move the same to

elevate buttons to said guideway, of a kicker 50 member movable to kick improperly positioned buttons from said guideway, said member having a projecting part without the hopper, means normally retaining said member in inoperative position, and a pawl 55 carried by said lever and operable upon a slide raising movement of said lever to move said member to operative position and then to release it to permit its return to inoperative position.

3. In a machine of the class described, the combination with a hopper having a button delivery guideway therein and a button elevating slide within said hopper, of a kicker member movable up through a portion of said guideway to eject improperly positioned buttons therefrom, means normally retaining said member in lowered position, and means having connection with both said elevating slide and said member 70 and operable to reciprocate said slide and to raise said member to button ejecting position and then to release the same, said release taking place before said slide has reached the limit of its raising movement. 75

4. In a machine of the class described, the combination with a button hopper having a button delivery guideway therein, and a button elevating slide movable in said hopper, of a kicker member movable up 80 through a portion of said guideway to eject improperly positioned buttons therefrom, said member having an outwardly projecting lip at its lower end, means normally retaining said member in lowered position, a lever having connection with said slide and operable to raise and lower the same, and a pawl pivotally carried by said lever for limited rocking movements relative thereto and operable upon a slide raising movement of said 85 lever to coact with said member lip to raise the member to operative position and to disengage said lip at a predetermined point in the slide raising movement of said lever. 90

In testimony whereof I have hereunto signed my name to this specification.

LE DRU R. POMEROY.
